[57] CLAIM

The ornamental design for a case for writing instruments, as shown and described.

DESCRIPTION

FIG. 1 is a front elevational view of a case for writing instruments showing my new design, with the cover in the closed position;

FIG. 2 is a top plan view thereof;

FIG. 3 is a bottom plan view thereof;

FIG. 4 is a right side view thereof, the left side view being identical thereto;

FIG. 5 is a rear elevational view thereof;

FIG. 6 is a vertical sectional view thereof;

FIG. 7 is a front elevational view of the body portion of the case for writing instruments shown in FIG. 1;

FIG. 8 is a top plan view thereof;

FIG. 9 is a bottom plan view thereof;

FIG. 10 is a right side view thereof, the left side view being identical thereto;

FIG. 11 is a rear elevational view thereof;

FIG. 12 is a front elevational view of the cap portion of the case for writing instruments shown in FIG. 1;

FIG. 13 is a top plan view thereof;

FIG. 14 is a bottom plan view thereof;

FIG. 15 is a right side view thereof, the left side view being identical thereto;

FIG. 16 is a rear elevational view thereof;

FIG. 17 is a vertical sectional view thereof as viewed from the right;

FIG. 18 is a perspective view as viewed from the right front of the case for writing instruments shown in FIG. 1; and

FIG. 19 is a further perspective view as viewed from the top front showing the case for writing instruments of FIG. 1 in the open position and a portion of the cap.
